UNITED STATES PATENT OFFICE

2,177,664

DISTILLATION AND PURIFICATION OF CARBONIZABLE ORGANIC MATERIALS

Alan Porter Lee, New York, N. Y.

Application June 24, 1936, Serial No. 86,912

6 Claims. (CL 202—53)

This invention relates to improvements in methods of distillation and purification of such organic materials as are readily charred or carbonized when heated to temperatures in the neighborhood of their volatilization points, more particularly when subjected to local overheating due to unequal contact with the heat transfer medium. An important example of such materials is found in mixed fatty acids, the product 10 of hydrolysis of tallow, greases, fatty oils, soapstocks and similar products.

Distillation of such mixed fatty acids in batch, or semi-continuous processes has been carried out in industry for many years in various countries, 15 the methods being well-known to those skilled in the art. The usual equipment heretofore employed has been a fireheated batch-type steam still operated under atmospheric or subatmospheric pressure. Superheated steam has been 20 generally injected into the mass of material in the still in order that the partial pressure of the steam may reduce the distillation temperature. Condensation has been carried out generally in tubular surface condensers interposed between 25 the still and the vacuum-producing apparatus, if vacuum is employed, or merely connected to the vapor outlet of the still in atmospheric distillation outfits. In the distillation of fatty acids in such apparatus there has been considerable loss due to 30 local overheating of the still bottom, particularly of the film of material directly adjacent to the bottom; also in a considerable zone near it. This overheating has caused marked charring and degradation of the stock being distilled, resulting 35 in low yields of distilled products and high yields of tar or pitch. There has been also considerable damage to the still itself, necessitating frequent renewal of the still bottom.

In recent years various efforts have been directed toward improvement of equipment and processes for distillation of fatty acids and similar materials. Most methods proposed have attempted to reduce the percentage of carbonization by 40 reducing the time during which the stock to be distilled is subjected to heating action, chiefly by heating said stock while it is in motion through a heating zone and removing the distillate vapors from a vaporization chamber placed between the heating zone and the condensing equipment. 45 In working toward this result, those skilled in the art have turned to the well-known tube and tower principle, in which the stock to be distilled is allowed to flow through a tube or series of tubes in a heating zone, then to expand into a vacuum 50 chamber, in which a stream of superheated steam

(or other inert gas or vapor) is permitted to contact the heated stock, intimate contact being secured by baffles or other well-known means of securing counter-current travel and intimate admixture of the steam with the heated stock. 5

In commercial application of these principles to the distillation of fatty acids and other similar delicate organic products, one of the difficulties to be overcome is local overheating of the charge in the course of passage through the tubes of the 10 heating zone, due to the difficulty of preventing the formation of a sluggish film of material on the inner surface of the tube. It is a well-known principle of chemical engineering that no matter how turbulent the flow of the main body of a 15 stream through a tube, there must be a film of fluid moving in viscous or sluggish flow in the outer annular portion of the cross-section of the tube, that is, near the wall of the tube. The rate of heat transfer through such a film is very 20 low, therefore when it is necessary to heat the entire contents of the tube to a temperature near the decomposition point there is great danger of decomposing and (in the case of delicate organic materials) carbonizing the material in the film. 25 Such carbonizing is progressive and once started, rapidly proceeds toward the center of the tube as new and thicker sluggish films are formed on the rough surface of the carbon which becomes deposited upon the inner surface of the tube. It 30 becomes apparent, then, that in applying heat to a tube heater for distillation of those organic products which decompose at temperatures only slightly above their respective vaporization points, it is necessary to control the temperature of the 35 heat transfer medium within very close limits, relatively near the temperature desired in the heated stock, or to seek means of overcoming the above-described film effect.

Methods proposed for close control of heating 40 in a tube for distillation purposes have included such expedients as—

1. Immersion of the tube in a lead or oil bath, heated by suitable means.
2. Transfer of heat to the tube through the 45 medium of superheated steam, which is in turn heated by gases of combustion in a suitable furnace.

3. Heating by transfer exchange with hot liquids through shell-and-tube or double-tube heat 50 exchangers.

The present invention provides means of overcoming the film-effect which promotes local overheating and carbonization in the tube, thus permitting the use of such economical means of heat 55

transfer to the stock in the tube as is provided by gases from the combustion of any suitable fuel. This invention also provides new methods of condensation which facilitate the production of an improved distillate and a new method of circulating, reheating and redistilling bottom residuums, thus reducing the length of vaporization chamber necessary to secure complete distillation.

10 An example of the operation of my process is given below in a description of operation of the process in distillation of mixed fatty acids, but it is to be understood that the invention is applicable to other organic materials of similar characteristics and is not limited to fatty acids.

15 In order that my invention may be clearly understood, I refer to the drawing herewith in which:

20 Figure 1 is an elevation, partly in section, of the apparatus in one form of design.

Figure 2 is a detail of one form of the steam or inert gas atomizer for atomization of the material to be distilled.

25 Referring to Figure 1, which is an elevation, partly in section, of suitable equipment for carrying out of my process, pipe-line 1 is the charging line through which the mixture of fatty acids or fatty-acid-containing stock is fed to the apparatus by gravity or by other suitable means. In the 30 usual operation of commercial fatty acid distillation the stock fed may contain from 90% to 98% of mixed fatty acids, the remainder consisting of neutral fat, unsaponifiable material and traces of moisture. The material fed into the system through charging line 1 may be at any suitable 35 temperature for its pipe-line flow, varying from room temperature for liquid fatty acids to 150°-175° F. for higher melting mixtures. The stock to be distilled is fed thus through pipeline 1 into and 40 through the shell-and-tube heat exchanger 2, where it is heated by means of any suitable hot fluid, preferably steam, to any convenient temperature of initial heat or preheat, such as 225° to 300° F., and preferably not over 275° F., for avoidance of local overheating and consequent decomposition. The temperature of the heating fluid 45 may be from 300° to 375° F. or lower, but not substantially higher.

50 From the preheater 2 the stock to be distilled passes through the pipeline 3 to the atomizer 4, where it is thoroughly mixed, atomized and sprayed with from five to fifty or more times its own volume of steam. The effect of this atomization is to break up the solid stream of flowing 55 liquid into a mist or spray of dissociated liquid particles or droplets, each being fully surrounded and encased by a protective atmosphere of steam. In this mixture the steam forms a continuous phase and the stock a discontinuous phase consisting of a plurality of separate particles. The 60 possibility of formation of any film of liquid on the interior surfaces of the tubes 5, 5 in the heater, through which the mixture next passes is thus avoided. In this manner any local overheating, 65 decomposition, charring or carbonization, is prevented. The atomization with steam also increases the velocity of flow and the turbulence, thus contributing further to the avoidance of film formation in the tubes of the heater.

70 The atomization of the stock with steam may be accomplished by any suitable means, such as a steam ejector, revolving vanes, spray nozzles, mixing valve, burner-type atomizer or any suitable combination of such means. In the process here- 75 in described the atomizing means consists of a

steam-ejector-type mixing valve as shown in cross-section in Figure 2.

The preheated charging stock is supplied under pressure through pipe 3 while superheated or saturated steam is supplied at slightly higher pressure through valve b. Valve c is a throttle valve by means of which the volume of steam used in mixing can be regulated within close limits. The steam passing through the constricted throat d exerts a suction effect upon the stock surrounding the nozzle e in the chamber f, drawing the stock in the form of fine atomized drops or particles through the close clearance g surrounding the nozzle e and on into the pipe 5. The volume of steam being many times that of stock, the resultant mixture consists of many particles of stock surrounded by an atmosphere of steam. Other suitable means of atomization may be substituted for that shown.

20 For the steam used for atomization, any inert gas, such as nitrogen, might be substituted, in which case the atomizing gas would preferably be preheated to a temperature equal to or slightly higher than that of the stock to be atomized. When steam is used it may be saturated or slightly 25 superheated steam.

25 The atomized mixture of stock and steam passes through the heating tubes 5, 5 of the mist heater coil, (Figure 1), being heated therein by direct contact on the outer walls of the tubes of the gases 30 of combustion of suitable fuel, as for example, natural gas, fuel oil or coal. In one application of my invention, waste gases which have previously been utilized for superheating steam are employed to heat the mixture of steam and fatty acids passing through the tubes 5, 5, means being provided to control the temperature of the gases when contacting the tubes 5, 5, raising this temperature by admission through bypass 10 (shown in closed position) of some gases not previously utilized and 40 lowering it by admission of air through the tempering damper or dampers, 11 and 11a. Suitable temperature of gases entering the stock-steam heater pass 9a have been found to be between 650° and 950° F., preferably 850° F. 45

50 The atomized mixture of steam and stock is heated very rapidly while passing through the tubes 5, 5 of the pass 9a, a convenient rate being about 800° F. per minute, the heating being carried to a point below the vaporization temperature 55 of the stock under the pressure conditions of the heater, but considerably above the vaporization temperature of the same stock under the sub-atmospheric pressure conditions which it next encounters in the distillation or flashing chamber 12. Suitable maximum temperatures for the atomized 60 stock and steam mixture when distilling fatty acids are from 400° to 600° F. and preferably 475° to 525° F., although depending in some measure upon the composition of the stock and the absolute 65 pressure conditions in the distilling apparatus. After being heated in the tubes 5, 5, where the pressure is maintained at an average of 8 lbs. per square inch gauge or less, the mixture of stock and steam passes through the pipe 6 and the control valve 8 into the distillation chamber 12, which is maintained under relatively low subatmospheric pressure, from 1" to 10" mercury absolute, and preferably about 2" absolute in its upper portion, although the operation may be performed at other 70 pressures, depending upon the amount of distillation steam employed. The distillation chamber may take any well-known form, as, for example, a plain cylinder, a tower packed with material for increasing evaporative surface, a screen-baffle 75

tower or a bubble-cap tray tower. In this instance the chamber is shown as a bubble-cap plate tower 12, having several plates 13, 13, each plate being equipped with a plurality of bubble-caps 14, 14 and vapor chimneys 15, 15. Each plate is equipped also with an overflow pipe 16.

When the atomized mixture of steam and stock enters the vacuum chamber 12 through the valve 8, the steam expands, and the stock, being above its volatilization temperature for the pressure conditions of the vacuum chamber, commences to volatilize rapidly. Both these conditions cause considerable drop in temperature in the stock, which drop amounts in practice to 40° to 90° F.

In the instance shown the stock and steam mixture is introduced just above the lowest upper tray 13c of the bubble tower. The steam and the immediately vaporized fatty acids rise in the tower toward the next tray above, while that part of the stock which remains unvaporized falls toward the tray 13c. The mixed vapors pass through the chimneys and caps in the next upper tray 13b and much of the vaporized fatty acids is condensed, forming on the tray a pool of fatty acids of considerably purer quality than the original stock. The depth of this pool is controlled by the overflow pipe 16b, which carries to the next lower tray all condensation in excess of the amount necessary to maintain a shallow pool on the upper tray 13b. The unvaporized stock likewise forms a pool on the first tray 13c below the feed inlet.

Steam at boiler pressure, in this case 145 lbs. per square inch gauge (temperature 363° F.) is taken from the steam header 7 through the pipe 17 and superheated in the pipe coil 18 in furnace 9 to final temperature of 900° to 1000° F. In passing through the pressure reducing and regulating valve 19, its pressure is reduced to 3-10 lbs. per square inch gauge and its temperature falls to 750°-900° F., normally 850° F. Any suitable fuel is burned at the burner 35 in furnace 9, the gases of combustion passing over the steam superheating coil 18 in space 36, then through pass 9a over the heating tubes 5, 5 through which latter tubes is passed the atomized stock-steam mixture which is to be distilled, the gases passing finally out through the breeching 38 and the stack 39. Control of temperature of the gases passing over the tubes 5, 5 is secured by means of the hot-gas bypass damper 10 and the tempering dampers 11 and 11a.

The reduced-pressure superheated steam is conducted through pipe 20, control valve 21 and nozzle 22 to the center of the tower 12 at a point just below the bottom bubble-cap plate 13f. This superheated steam serves two purposes, first, to aid distillation of the fatty acids and second, to supply heat to replace that consumed in evaporation of the stock and in radiation from the apparatus.

As the steam expands through the control valve 21 out of the supply pipe zone of pressure of 3 to 10 lbs. per square inch gauge, into the bottom area of the tower at pressure of 2½" to 3" of mercury absolute, there is marked cooling of the steam due to expansion, which enables regulation of the temperature of this bottom area at between 575° and 650° F., when using steam at temperatures between 800° and 900° F. before expansion into the tower.

When the pool of unvaporized stock on the tray 13c below the stock-steam inlet pipe becomes of depth just greater than the projection 75 above the tray of the top of the overflow pipe 16c,

the surplus stock overflows to the next lower tray 13d, where it forms a new pool of material lower in fatty acid content than the original stock. In similar manner pools are formed on each succeeding tray below the point where the atomized stock-steam mixture enters the tower.

As the superheated steam entering the bottom of the tower expands, rises through the bubble-cap chimneys and is distributed by the bubble-caps through the pool of material on the lowest tray, the bulk of the fatty acids remaining in this material will be vaporized, with the aid of the partial pressure of the superheated steam. The mixed steam and distillate vapors will rise through the chimneys of the next higher tray 15 and be distributed through the pool of material on that tray. Here portions of the distillate vapors will condense, giving off their heat of condensation to cause evaporation (with the aid of the partial pressure of the steam) of further 20 quantities of vaporizable material from the pool on that tray.

This process of condensation and evaporation is repeated on each succeeding bubble tray from bottom to top of the tower, the rising vapor mixture becoming progressively richer in distillate vapors as the top tray is approached and the descending unvaporized stock becoming progressively poorer in vaporizable material as it approaches the bottom tray.

The rising mixed vapors of superheated steam and distillate become progressively cooler as they pass upward through the tower, from the effects of expansion, evaporation and radiation. The descending stream of liquid material likewise 35 tends to become progressively cooler in descending through the tower, from the effects of evaporation and radiation. As the operation progresses, this tendency of the descending stock to become cooler is overcome, in part by the 40 heating effect of partial condensation of distillate vapors in the pool of liquid on each tray and partly by the heat supplied by the superheated steam, so that when the operation reaches the desired state of continuous equilibrium, the 45 descending liquid stock increases in temperature on each succeeding lower tray, while the ascending vapors decrease in temperature as they rise through the tower. The liquid residue flowing away from the bottom tray 13f, in fatty acid 50 distillation is at a temperature of 505° to 595° F. and preferably 580° F. when distilling standard mixed fatty acids from tallow grease. It is to be noted that for best results, this temperature of material leaving the bottom tray may suitably 55 be varied over a wide range, depending upon the type of material treated. For certain fatty acids of vegetable origin, this bottom tray temperature suitably may be carried as low as 400° F., or even 60 lower.

The residue flows from the bottom plate through the overflow pipe 16f into the cup seal 23, out of which it falls to the bottom of the tower, forming there a pool, the depth of which is controlled by the inverted siphon pipe-loop 24.

Another feature of my invention, is my method of recycling and reheating residues for further recovery of distillate therefrom. It is well known that almost any distilling column can be reduced in overall height and number of trays by refluxing a portion of the residue to the lower portion of the tower (below the feed inlet). In the distillation of fatty acids, tars, waxes and similar heavy, viscous materials, the residues are of such heavy, tarry nature, even at the elevated temper- 75

ture of the still, that recirculation by ordinary means becomes difficult and often impossible. In addition such residues tend to cool rapidly, becoming on cooling very much more viscous.

5 In my invention I utilize a lift-pump operated by superheated steam at a temperature considerably above that of the residues to draw such residues from the bottom of the vacuum chamber 12 through the skimming pipe 25 and the lift-pump 26, discharging through the discharge pipe 27 and the valve 28 into the distillation chamber at a point above the third tray from bottom, 13d, or alternatively to the next lower tray 13e through the valve 28a, or through both these 15 valves to both the trays simultaneously. Superheated steam at 3 to 10 lbs. gauge pressure and temperature of about 850° F. is taken from the pipeline 20 through the valve 29 and the pipe 30 for operation of the lift-pump 26.

20 The use of the lift-pump operated by superheated steam has several advantages. The temperature of the residues is raised, thus aiding further distillation of vaporizable material from these residues. The superheated steam used for 25 the lift-pump mixes with the residues and its vapor pressure is utilizable in the distillation from the trays above the point of its entrance into the tower. The addition of the extra heat units of this superheated steam is useful in 30 economical replacement of heat lost by radiation from the central and upper portions of the tower and in maintenance of vaporizing temperatures on the upper plates.

35 Despite the admixture of steam with the residues and the injection of this mixture into the median portion of the distilling zone, in my process no entrainment of coloring matter from the residues is apparent in the distilled fatty acid vapors leaving the upper exit of the tower.

40 By variation of the volume of superheated steam fed to the lift-pump, the quality and amount of final residue can be controlled, the amount recirculated controlling the net amount of final residue outflow. As the amount of material recirculated is increased, the amount of distillation steam added to the tower through the supply pipe nozzle 22 likewise must be increased, to provide for the increasing distillation burden on the lower trays. The amount of steam utilized 45 by the recycling lift-pump, however, is also used 50 as distillation steam and does not increase the total steam input which would be required to obtain comparable distillation results in similar apparatus without this feature.

55 The heavier residues, sinking to the lowest point of the pool formed on the tower bottom and comprising all surplus which is not recycled by the lift-pump 26, flow through the pipe 31 and inverted siphon 24 into the pitch receiver 32, which is connected to the tower 12 by the vacuum-vent pipes 33 and 33a. The pitch receiver is shut off intermittently from the vacuum tower and, by means of steam pressure through the line 34 from the header 7, the pitch is discharged from the receiver 32 to storage, through valve 75 and pipe 76. When the pitch receiver is being discharged, the residues are permitted to accumulate further in the bottom of the tower 12, to the extent of surplus above the amount being recirculated, without deleterious effect upon the color of the distillate. In fact, after the continuous operation of the distilling apparatus has become stabilized, a pool of residue is maintained on the bottom of the tower 12, to 70 the depth permitted by the height of the inverted 75

5 siphon loop 24. This pool is heated by the superheated steam issuing from the nozzle 22 just above the pool and is also heated by the metal of the tower bottom, which in turn, derives its heat from the superheated steam. In operation the temperature of the residue pool is maintained at from 15° to 50° above that of the partially finished stock on the bottom tray 13f.

10 The vapors of pure fatty acids or other distilled material, which are volatilized from the upper tray, 13a, of the flashing chamber, by heat from the condensation of less pure vapors in the pool of liquid on that tray, and which are mixed with vapors of superheated steam, may be freed 15 of entrained liquid by any well-known means (such as the baffle-plate 40 in this instance), and then condensed, also by any means well-known to those skilled in the arts of distillation; the final residual water vapors, which contain traces 20 of distillate, being condensed in the vacuum producing apparatus or allowed to escape to the atmosphere (in atmospheric pressure adaptations of my process).

25 In practice heretofore in fatty acid distillation it has been customary to condense the distillate 25 at such temperatures and pressures and under such conditions that the condensate obtained contained considerable liquid water or at least traces thereof.

30 Another new feature of my invention is a new 30 and unique means of distillate condensation, whereby the condensate in a distillation process is recovered entirely free of any trace of liquid water. Its application to the process of fatty acid distillation herein described is as follows: 35

35 As stated above, the pure distillate vapors mixed with superheated steam rise from the top tray 13a of the distillation chamber 12 (Figure 1). The mixed vapors travel through the annular space surrounding the entrainment baffle 40, 40 pass above the baffle and out of the distillation chamber through the vapor nozzle 41 and the elbow 42. Exit vapor temperature for fatty acids may be 375° to 475° F. (preferably 415° to 430° F. for the mixed fatty acids of tallow greases). 45

45 In applying the well-known water spray condensation system at points 43 and/or 44, 45, it was found that the distillate recovered in the receiver-separator 46 was small in quantity and contained appreciable amounts of free liquid water as well as some emulsified water. In my invention, surprisingly, I overcome these drawbacks entirely by heating the water used in the condensing sprays nearly to its boiling point at atmospheric pressure. This heated water is conveyed under positive pressure to the condensing spray-heads and when released through these spray-heads into the reduced pressure zone of the vapor pipes 47 and 48, all of the water is completely vaporized, absorbing the heat necessary for its vaporization from the mixed distillate and superheated steam vapors coming from the tower 12. This absorption of heat causes the bulk of the distillate vapors to condense as liquid, entirely free of any liquid water. This liquid condensate may be collected in the receiver-separator 46. 60

65 Description of the spray-condensation system as operated in my invention is as follows (refer to Figure 1):

70 Steam at 145 lbs. gauge pressure is taken from the main steam header 7 through the valve 49 and the pipe line 50 to the steam space of the preheater 2 where it is utilized to preheat the charging stock of the still by means of heat- 75

exchange. The steam condenses in the pre-heater and the condensate water is automatically removed through the pipe line 51 by the steam trap 52, discharging through the pipe line 53 into the reservoir 54. The pure condensed water is pumped by the pump 55 through the heating coil 56 in the heat exchanger 57 and on through the pipe line 58 to the spray nozzles at 43, 44 and 45. These nozzles may be utilized in any suitable manner, each being controlled by a valve. Steam, water or any suitable fluid may be used as the heating medium for the pure water passing through the coil 56. In the example shown, steam at 145 lbs. gauge pressure is taken from the steam main 7 through the pipe line 4a and reduced to 15 to 20 lbs. gauge pressure by means of the pressure-reducing and regulating valve 4b. A portion of this steam is utilized for atomization of the charging stock in the steam-atomizer 4 and another portion passes to the heat exchanger 57 through the pipe line 4c. In the heat exchanger 57, this steam is used to heat the water passing through the coil 56. This water is heated to 180° to 205° F. and preferably as high as possible without substantial vaporization in the coil 56 or the pipe line 58. Operation of the pump 55 is so controlled that a pressure of from 6 to 12 lbs., normally 8 lbs. gauge is maintained in the spray water supply pipe 58 at the gauge point 59 close to the spray-nozzle locations.

The means herein described for supplying hot water to the spray-nozzles is one example only and its description is not to be construed as limiting my invention, as any suitable means of heating the water may be employed, my invention being comprised in the heating of water or other vaporizable liquid for use in spray condensation, to insure full absorption of the latent heat of vaporization when the liquid is discharged through the spray-nozzle or other spray device. The sensible heat which is added to the water in the heating is so small in quantity in proportion to the latent heat which is absorbed when the water is vaporized that it is not an important factor.

If cold, or only moderately warm water is used for spray condensation in vacuum apparatus, the water will be vaporized eventually, but the advantage of using water or other liquid which has been heated to a temperature closely approaching its atmospheric vaporization point is to be found in the rapidity with which it will be completely vaporized under the reduced pressure conditions in the vacuum apparatus. It is obvious that the water or other liquid selected as a spray condensation means must have a vaporization point well below that of the distillate to be condensed and must have a relatively large latent heat of vaporization. The practical advantages resulting from rapid and complete vaporization of the cooling medium are three-fold: first, reduction in necessary size of efficient apparatus; second, complete availability of the latent heat of vaporization for cooling and condensing purposes; third, complete freedom of the condensate from traces of the cooling liquid.

The spray condensing system may be combined with any suitable collecting system for recovery of the condensed distillate. In the example shown (Figure 1), the mixed vapors of steam and distillate entering the outlet pipe 41 at 415° to 430° F., are cooled to 325° to 365° (normally 350° F.) by means of the hot-water sprays 43, 44 and 45. Passing through the vapor pipe 47 into the receiver-separator 46, the bulk

of the distillate vapors separates out as liquid fatty acids in the receiver-separator, from which the liquid condensate flows by gravity through the pipeline 60, the shell-and-tube cooler 61 and the pipe 62 to the collector 63. In passing through the shell-and-tube cooler 61, the liquid condensate is cooled to 125° to 175° (normally 135° F.) by means of water or other cooling fluid and collected in a pure moisture-free state in the collector 63. From this container it may be pumped continuously by means of the pump 64 and the pipe 65 to a receiving and storage tank (not shown). The collector 63 is joined to the receiver-separator 46 by the additional vacuum-vent pipe 66.

After collection of the bulk of the condensed distillate in the receiver-separator 46, the residual water vapors, containing a small percentage of uncondensed distillate vapors, pass through the vapor pipe 48 to the shell-and-tube condenser 67, where the vapor stream is further cooled to 115° to 140° F. (normally 120° F.), by heat exchange with water or other suitable cooling fluid. Here the remaining distillate vapors are condensed, the liquid condensate collecting in the hot-well receiver 68 and flowing by gravity through the pipe 69 to the second collector 70, from which this condensate is pumped continuously through the pipe 71 by means of the pump 72 to a receiving and storage tank (not shown). The second collector 70 is connected to the shell-and-tube condenser 67 by a vacuum-vent pipe 73 in addition to the pipe 69. The distillate condensed in the shell-and-tube condenser and collected in the second collector 70 generally contains small quantities of liquid water, but the total of this condensate is a very small fraction of the total from the still, the bulk of the distillate vapors being condensed by the spray condensing system.

The final water vapor, practically free of distillate (vapor or liquid), leaves the shell-and-tube condenser 67 by the vapor pipe 74, passing to standard vacuum apparatus of any suitable type (not shown).

As an example of operation under the process hereinbefore described, the following distillation has been carried out. The distilling bubble tray column utilized was approximately 15' high and 6'6" in internal diameter at the top (cross sectional area 33.2 square feet). The tower contained six bubble trays spaced 22" apart, the bottom tray being 30" above the bottom of the tower. The upper tray contained 84 bubble caps, each cap being 5" in external diameter. The total effective distilling area of the upper plate was therefore 21.75 square feet. The top vapor outlet of the tower was 16" internal diameter. Below the vapor outlet a conical shaped baffle plate 41" in greatest diameter was inserted. The annular space through which all vapors passed between this baffle plate and the upper portion of the tower wall was 28.25 square feet in area.

Steam was admitted to the tower through a 3" pipe below the bottom tray, but above the maximum height of the pool of residue on the bottom of the tower. The material to be distilled, after atomization by steam, was admitted to the heater through two two-inch tubes in parallel and after leaving the heating zone the two portions were combined in one three-inch pipe through which the mist of atomized fatty acids and steam entered the distilling tower in its upper portion. Pressure slightly in excess

of atmospheric was maintained in the tubes of the heater.

During a continuous run of 91½ hours, 180,900 pounds of Twitchellized brown grease fatty acids containing 96.2% of free fatty acids (calculated as oleic acid), were fed to the still, or at an average rate of 1977 pounds per hour. 173,390 pounds of distillate were recovered, having color of between 1 and 1½ A. S. T. M., representing a yield of 95.8%. (A. S. T. M. refers to the color standards of the American Society for Testing Materials, which are well-known to those skilled in the art of distillation.)

During this period 3202 lbs. of steam were fed to the charge through the atomizing device, an average of 35 lbs. per hour.

There was added also a total of 86,790 lbs. of superheated steam (an average of 948.5 lbs. per hour), through the three-inch pipe at the bottom of the tower and through the bottoms recirculating lift-pump. The stream of fatty acids entered the steam preheater at about 160° F. and was heated therein to temperature of 215° to 230° F. with normal temperature of 225° F. It then passed to the atomizing and steam-mixing valve wherein it was atomized and thoroughly mixed with an average of 35 lbs. of steam per 1977 lbs. of charge, or approximately 29 parts of steam by volume to each part of fatty acid charge.

This atomized mixture of fatty acids and steam entered the heating mist-heater tubes 5, 5 at a temperature of 227° F. and was heated therein to 495° to 530° F. with a normal temperature of 510° F. Passing then to the distilling column through the line 6 and the valve 8, the atomized mixture entered the column above the tray 13c and was cooled by expansion and evaporation so that the temperature of the liquid pool formed on the tray 13c was 425° to 440° F., normally 430° F.

A large portion of the fatty acids was vaporized at once and passed upward as vapor through the distilling column. The unvaporized portion formed a pool on the tray 13c and overflowed therefrom to the lower trays in succession. As the unvaporized residue of the stock descended through the tower, successive additional portions of the fatty acids were vaporized from each tray and the temperature of the residue gradually rose until on the bottom tray (13f) the temperature was 525° to 550° F. with normal temperature of 525° F. From this tray the remaining unvaporized residue overflowed into the cup 23 and thence to the bottom of the tower. When the pool of residue so formed in the bottom of the tower reached the height of the intake of pipe 25, 4 inches above the bottom of the tower, the lift-pump 26 commenced drawing the residue through the pipe 25, mixing it with superheated steam to reheat it and discharging it above the plate 13d where it joined the stream of unvaporized stock descending through the distilling column. When the total of unvaporized stock descending in the tower became greater than the amount returned by the lift-pump to plate 13d, a pool was formed in the bottom of the tower. The depth of this pool was controlled (by the outlet pipe loop 24) at 13 inches above the bottom of the tower. When the pool started to exceed this depth, all surplus unvaporized residue flowed from the bottom of the pool through the pipe loop 24 into the pitch receiver 32, whence it was discharged intermittently to a storage tank (not shown) by means

of steam pressure admitted to the receiver 32 from the pipeline 34.

By means of the superheated steam entering the distilling column and in the lift-pump 26, the temperature of the recycling stock and of the descending stock in the lower portion of the column was gradually raised until the temperature on the bottom tray became 580° to 610° F., normally 595° F. and the temperature of the pool of residue in the bottom of the tower became 610° to 635° F., normally 615° F.

The vapors rising in the distilling column had an exit temperature of 410° to 430° F., normally 420° F. and were cooled immediately upon leaving the tower, so that the residual vapors leaving the receiver-separator 46 had a temperature of 340° to 367° F., normally 350° F. In the shell-and-tube condenser 67, the vapors were further cooled to an exit temperature of 115° to 140°, normally 125° F. and here substantially the entire remainder of the uncondensed fatty acid vapors was condensed, collecting in the hot-well 68 and flowing to the second collector 70. The condensed fatty acids flowing from the receiver-separator 46 were cooled in the shell-and-tube cooler 61 to 125° to 160° F., normally 135° F. This condensate was free of water. The condensates from both collectors were pumped to a single storage tank, where they were combined in anticipation of further processing or shipment.

The temperature of the water used in the sprays was 198° to 200° F., normally 200° F. The pressure of this water in the supply pipe near the spray-outlets was 3 to 8 lbs. per square inch, normally 6 lbs. per square inch, above atmospheric pressure.

The plant steam pressure utilized was 148 lbs. per square inch gauge with total temperature of 365° F. The superheated steam had pressure of 6.5 lbs. gauge and temperature of 850° F. before entering the bottom of the tower and the lift-pump, variations of pressure being observed between 5 lbs. and 7 lbs. gauge and temperature range from 830° to 880° F. The pressure of steam before entering the atomizing mixer was 18 lbs. gauge, temperature 255° F.

Absolute pressures maintained in the system were as follows:

	Inches of mercury	50
At the vacuum condenser	0.5	
At the shell-and-tube condenser	1.0 - 1.5	
At the receiver-separator	1.5 - 2.0	
At the tower top	1.75 - 2.25	
At the tower bottom	2.5 - 3.0	55

The yield was as follows:

	Pounds	Percent	60
Distillate	173,390	95.8	
Pitch	6,645	3.7	
Loss	865	0.5	

My new process may be used likewise in other distillations where it is desirable to protect the charge from local overheating in passing through tubes in a heating zone. It may be used also for the deodorization and/or purification of fatty oils or mineral oils or other delicate organic substances containing volatile components. The fatty acids mentioned in the foregoing can be substituted, for instance, by petroleum oils, particularly lubricant stocks, or by glycerine, without any change of procedure other than those which would be evident from a knowledge of the 75

chemical and physical properties of those materials.

The foregoing detailed description has been given only for clarity of understanding and no unnecessary limitations should be understood therefrom, but the appended claims should be construed as broadly as permissible, in view of the prior art.

What I claim is:

1. In a process for distillation of organic liquids with avoidance of decomposition, the steps which comprise atomizing such liquid at atmospheric or higher pressure with not less than approximately five times its own volume of suitable inert gas to form an atomized mist consisting of a continuous phase of said inert gas containing and surrounding a discontinuous phase of said liquid, heating said atomized mist as such in a continuous tubular structure to a temperature below the initial vaporization temperature of said liquid at the pressure of said heating, but which temperature is higher than the initial vaporization temperature of said liquid at a subsequent sub-atmospheric distilling pressure and is within the normal temperature range of incipient decomposition of said liquid if subjected to flow as a liquid stream through a heated tube, expanding said heated atomized mist through suitable control means into a distilling zone of sub-atmospheric pressure and passing inert gas into said distilling zone to promote vaporization of liquid from said atomized mist.

2. In a process for distillation of fatty acids with avoidance of decomposition, the steps which comprise atomizing material containing fatty acid at atmospheric or higher pressure with not less than approximately five times its own volume of suitable inert gas to form an atomized mist consisting of a continuous phase of said inert gas containing and surrounding a discontinuous phase of said material, heating said atomized mist as such in a continuous tubular structure to a temperature below the initial vaporization temperature of the contained fatty acid at the pressure of said heating, but which temperature is higher than the initial vaporization temperature of said fatty acid at a subsequent sub-atmospheric distilling pressure and is within the normal temperature range of incipient decomposition of said material if subjected to flow as a liquid stream through a heated tube, expanding said heated atomized mist through suitable control means into a distilling zone of sub-atmospheric pressure and passing inert gas into said distilling zone to promote vaporization of fatty acid from said atomized mist.

3. The process for distillation of organic liquids with avoidance of decomposition which comprises moderately preheating such liquid below its vaporizing temperature, atomizing a flowing stream of said preheated liquid at atmospheric or higher pressure with not less than approximately five times its own volume of suitable inert gas to form an atomized mist comprising a continuous phase of said inert gas containing and surrounding a discontinuous phase consisting of discrete particles of said liquid, heating said atomized mist as such in a continuous tubular structure to a temperature below the initial vaporization temperature of said liquid at the pressure of said heating, but which temperature is higher than the initial vaporization temperature of said liquid at a subsequent sub-atmospheric distilling pressure and is within the nor-

mal temperature range of incipient decomposition of said liquid if subjected to flow as a liquid stream through a heated tube, expanding said heated atomized mist through suitable control means into a distilling zone of sub-atmospheric pressure, passing inert gas into said distilling zone to promote vaporization of liquid from said atomized mist, passing the vapors of distillation into a condensing zone and condensing and removing the resultant distillate.

4. The process of distillation for obtaining purified fatty acid from material containing fatty acid with avoidance of decomposition which comprises moderately preheating such material below the initial vaporizing temperature of its contained fatty acid, atomizing a flowing stream of said preheated material at atmospheric or higher pressure with not less than approximately five times its own volume of suitable inert gas to form an atomized mist comprising a continuous phase of said inert gas containing and surrounding a discontinuous phase consisting of discrete particles of said material, heating said atomized mist as such in a continuous tubular structure to a temperature below the initial vaporization temperature of the contained fatty acid at the pressure of said heating, but which temperature is higher than the initial vaporization temperature of said fatty acid at a subsequent sub-atmospheric distilling pressure and is within the normal temperature range of incipient decomposition of said material if subjected to flow as a liquid stream through a heated tube, expanding said heated atomized mist through suitable control means into a distilling zone of sub-atmospheric pressure, passing inert gas into said distilling zone to promote vaporization of fatty acid from said atomized mist, passing the vapors of distillation into a condensing zone and condensing and removing the resultant fatty acid.

5. The process for distillation of organic liquids with avoidance of decomposition which comprises moderately preheating such liquid below its vaporizing temperature, atomizing a flowing stream of said preheated liquid with not less than approximately five times its own volume of suitable inert gas to form an atomized mist comprising a continuous phase of said inert gas containing and surrounding a discontinuous phase consisting of discrete particles of said liquid, heating said atomized mist as such in a continuous tubular structure to a temperature below the initial vaporization temperature of said liquid at the pressure of said heating, but which temperature is higher than the initial vaporization temperature of said liquid at a suitable subsequent reduced distilling pressure and is within the normal temperature range of incipient decomposition of said liquid if subjected to flow as a liquid stream through a heated tube, expanding said heated atomized mist through suitable control means into a distilling zone maintained at pressure lower than the pressure normally prevailing in said continuous tubular structure, vaporizing liquid from said heated atomized mist in said distilling zone, passing the vapors of distillation into a condensing zone and condensing and removing the resultant distillate.

6. The process of distillation for obtaining purified fatty acid from material containing fatty acid with avoidance of decomposition which comprises moderately preheating such material below the initial vaporizing temperature of its contained fatty acid, atomizing a flowing stream of

said preheated material with not less than approximately five times its own volume of suitable inert gas to form an atomized mist comprising a continuous phase of said inert gas containing and surrounding a discontinuous phase consisting of discrete particles of said material, heating said atomized mist as such in a continuous tubular structure to a temperature below the initial vaporization temperature of said fatty acid at the pressure of said heating, but which temperature is higher than the initial vaporization temperature of said fatty acid at a suitable subsequent reduced distilling pressure and

is within the normal temperature range of incipient decomposition of said material if subjected to flow as a liquid stream through a heated tube, expanding said heated atomized mist through suitable control means into a distilling zone maintained at pressure lower than the pressure normally prevailing in said continuous tubular structure, vaporizing fatty acid from said heated atomized mist in said distilling zone, passing the vapors of distillation into a condensing zone and condensing and removing the resultant fatty acid distillate. 5 10
